DERRICK

James F. Chappell, Mineola, Tex., assignor of one-half to Alvin H. Lane, Dallas, Tex.

Application January 11, 1937, Serial No. 120,003

12 Claims. (Cl. 212—71)

This invention relates to new and useful improvements in derricks.

One object of the invention is to provide a derrick having an improved sheave structure at its upper end, whereby two draw works may be employed for pulling drill pipe or tubing, making up joints, or for other well operations, thereby minimizing the time consumed for such operations.

10 An important object of the invention is to provide an improved derrick having a pair of crown block units movably mounted on its upper end, whereby one of the units may be centered within the derrick to support the drill pipe or tubing while the other unit may be off-center at the same time so as to be free for other work.

Still another object of the invention is to provide an improved derrick having a pair of crown block units mounted thereon with means for 10 moving the units either simultaneously or independently of each other to a desired position on the derrick, said means being controlled from any position on the derrick or from the derrick floor.

15 A further object of the invention is to provide an improved derrick having a pair of crown block units each of which have a line or cable threaded thereover, whereby each line may operate individually without interfering with the other; the arrangement being such that, if desired, both lines may be used together when a particularly heavy load is to be lifted or moved.

A construction designed to carry out the invention will be hereinafter described, together with 5 other features of the invention.

The invention will be more readily understood from a reading of the following specification and by reference to the accompanying drawings, in which an example of the invention is shown, and 10 wherein:

Figure 1 is a side elevation of an improved derrick constructed in accordance with the invention,

5 Figure 2 is an elevation taken at a right angle to Figure 1,

Figure 3 is a plan view,

Figure 4 is an elevation of the upper portion of the derrick as shown in Figure 1 with the crown block units shifted to another position,

0 Figure 5 is an enlarged, transverse, vertical, sectional view, taken on the line 5—5 of Figure 2,

Figure 6 is an enlarged, transverse, vertical, sectional view, taken on the line 6—6 of Figure 3, and

5 Figure 7 is a modified form of the invention.

In the drawings, the numeral 10 designates a derrick structure which includes vertical inclined legs 11 suitably connected together by horizontal girts 12 which are bolted thereto. The usual cross braces or struts 13 brace the derrick legs throughout their length. The lower end of the derrick is supported on the usual derrick floor 14 and it is noted that the structural details of the bracing employed in forming the derrick is subject to variation.

10 It is preferable that the derrick be substantially rectangular in cross section and the upper end of the derrick legs 11 are connected by longitudinal angle bars 15 which are secured by welding or otherwise to said legs. The ends of 15 the angle bars 15 are connected by transverse bars 16, as is clearly shown in Figure 3. The angle bars 15 not only serve to connect the upper ends of the derrick legs together but also act as guide rails for crown block units A and B, as will be explained.

The crown block unit A includes a rectangular frame 17 which has its end supported on the angle bars or rails 15, whereby said frame is 20 slideable longitudinally on said bars. With such arrangement it is possible to move the frame 17 to any position with relation to the center of the derrick. A transverse shaft 18 extends across the frame 17 at substantially the center thereof and a plurality of sheaves or pulleys 19 are journaled 25 on said shaft. A cable or line 20 has one end secured to the derrick leg and is threaded over the pulleys 19 and is also passed around the sheaves or pulleys 21 of a traveling block 22, which block has the usual hook 23 at its lower end. The other end of the cable or line 20 extends downwardly throughout the length of the derrick structure and is wound around the usual drum 24 of an ordinary draw works 25. The drum 24 and the mechanism for operating the 30 same is subject to variation but it is obvious that when said drum is rotated the line or cable 20 is either wound therearound or unwound therefrom. This causes the traveling block 22 to be raised or lowered within the derrick in the usual 35 manner.

Since the frame 17 of the unit A is movable transversely of the derrick along the bars or rails 15, it is obvious that the pulleys or sheaves 19 mounted within said frame are also movable 40 transversely of the derrick. Any suitable means may be employed for controlling the movement of the unit A, but I prefer to employ a piston 26 which is mounted to reciprocate within a cylinder 27. As clearly shown in Figures 1 and 4 the 45

cylinder 27 is mounted horizontally at the upper end of the derrick, being supported by suitable braces 28. The piston is provided with an axial piston rod 29 which extends from the inner end 5 of the cylinder 27. The outer end of the rod 29 is welded or otherwise suitably secured to the frame 17 of the unit A. It will be manifest that when the piston 26 is moved within its cylinder 27 a movement will be imparted to the unit A due to 10 the connection of the frame 17 with the rod 29.

Any suitable means may be employed for imparting a motion to the piston 26 to properly adjust the position of the unit A on the rails or bars 15 of the derrick, but I prefer to employ a pressure means. For this purpose a hose or conduit 30 has one end connected to one end of the cylinder 27. The other end of the hose leads to a source of pressure supply not shown, and a suitable control valve 31 is connected in said hose. A 20 similar hose or conduit 32 has its upper end connected to the other end of the cylinder 27 and is similarly provided with a control valve 33. The opposite end of this hose is, of course, connected to the source of pressure supply. With this 25 arrangement, it is obvious that if pressure is introduced through the hose or line 30 by opening the valve 31 the piston 26 will be moved toward the outer end of the cylinder 27 or to the left in Figure 1, whereby the unit A will be moved to 30 the left side of the derrick (Figure 1). Obviously, if the pressure is introduced through the other hose or line 32 then the piston 26 will be moved in an opposite direction, whereby the unit A is moved toward the center of the derrick. By 35 properly controlling the introduction of pressure to the cylinder 27 it is possible to accurately adjust the position of the unit A with relation to the center of the derrick.

The unit B is constructed in exactly the same 40 manner as is the unit A and includes a frame 34 having a transverse shaft 35 extending thereacross. A plurality of sheaves or pulleys 36 are mounted on this shaft. A cable or line 37 having one end secured to one of the legs 11 of the derrick is passed over the pulleys or sheaves 36 and around the sheaves 39 of a traveling block 40, which block has the usual hook 41 at its lower end. The other end of the line or cable 37 extends downwardly throughout the length of the 45 derrick and is wound around a drum 42 of a draw works 43 which is similar in construction to the draw works 25. It will be seen that by operating the drum 42 the cable is either wound therearound or unwound therefrom to control the 50 movement of the traveling block 40 within the derrick.

The frame 34 of the unit B is of course, slideable on the bars or rails 15 in the same manner as is the frame 17 of the unit A. For controlling 55 the movement of the unit B a cylinder 44, similar to the cylinder 27 is mounted at the other side of the derrick in the same manner as is the cylinder 27. A piston 45 is movable within the cylinder and has its rod 46 extending from the inner end of said cylinder and secured to the frame 34 of the unit B. As the piston 45 moves within its cylinder 44 the unit B is moved along the rail whereby its position with relation to the center of the derrick is varied. A pressure fluid line 47 has its upper end connected to the outer 60 end of the cylinder 44 and has its lower end connected to the line or hose 30 which leads to the inner end of the cylinder 27. A similar line or hose 48 has one end leading from the inner end 65 of the cylinder 44 and its other end connected

with the line or hose 32. With such arrangement it will be obvious that when the pressure fluid is introduced through the line 30 to the inner end of the cylinder 27, said fluid is at the same time, introduced into the outer end of the cylinder 44. 5 Therefore as the piston 26 moves outwardly in its cylinder, the piston 45 moves inwardly within its cylinder. When the pressure fluid is introduced into the line 32 and 48 an opposite movement of the pistons occur. Therefore, it will be 10 seen that as one unit is moving towards the center of the derrick the other unit is moving outwardly toward one side thereof.

It is particularly noted that the lines 47 and 15 48 are connected to the lines 30 and 32 respectively, between the control valves 31 and 33 and the pressure fluid supply. Suitable control valves 47' and 48' are connected in the lines 47 and 48 respectively, whereby either of the pistons 26 or 44 may be moved independently of the other. 20 By properly manipulating the various control valves it is possible to admit the pressure to only one of the cylinders 27 or 44 and therefore either one or the other of the units A and B would be inactive while the other was moving.

In Figures 1 to 6 the units A and B are shown as capable of either independent operation or of simultaneous operation. It would be possible to eliminate the independent movement of the units 25 with relation to each other by merely omitting the piston 45, cylinder 44 and their associate parts. In such case the frame 17 of the unit A and the frame 34 of the unit B could be connected together by a connecting bar 49 as shown in Figure 7. In such case the movement of the piston 30 26 within the cylinder 27 would move both units A and B simultaneously.

From the above, it will be seen that a derrick is provided wherein a pair of crown block units are mounted to move transversely thereof at its upper end. Each unit is complete in itself including the usual traveling block and having an individual cable or line which is operated from an individual or independent draw works. Therefore each unit can perform any work or drilling 40 operation without the aid of the other.

In operation, it will be assumed that the units A and B are in the position shown in Figure 1, with the unit A at one side of the derrick and the unit B at the center thereof. It will be further assumed that the usual swivel and Kelly joints 50 are suspended from the hook 41 of the traveling block 40 of the unit B. The kelly is of course connected to the upper end of the drill pipe 51 and extends through the rotary table 52 whereby the drilling operation may be performed. As the drilling continues the kelly will of course move downwardly through the rotary table in the usual manner and at this time the unit A is put into operation. That is, the traveling block 55 22 of the unit A is lowered to pick up another Kelly joint (not shown) which has a section of drill pipe connected to its lower end. The block has been raised so that the kelly and section of pipe will hang vertically at one side of the derrick in readiness to be connected in the string when the upper end of the Kelly joint 50 has reached the rotary table. When this occurs, the drum 42 is rotated to raise the traveling block 40 of the unit B whereby the kelly and drill pipe are pulled 70 out of the hole. The kelly 50 is then disconnected from the upper end of the drill pipe in the usual manner and the unit B shifted to the position shown in Figure 4 to swing the kelly to one side of the derrick out of alignment with the drill 75

5 pipe descending into the hole. At the same time that the unit B is shifted, the unit A is shifted from its position in Figure 1 to the position shown in Figure 4 which is centrally of the derrick. The 10 lower end of the pipe section which is suspended from the kelly on the hook 23 of the unit A is then coupled to the upper end of the drill pipe from which the kelly 50 has been disconnected. After this connection is made, the drum 24 of 15 the draw works 25 is rotated to lower the entire drill string with the new section and second kelly connected thereto. After being lowered to its proper position the drilling operation then continues and as the kelly suspended from the unit 20 A is again moving downwardly through the rotary table, the unit B is utilized to connect another section of drill pipe to its kelly 50, whereby this new section is in readiness for connection into the drill string when necessary.

25 Obviously with this arrangement, a great saving of time in making up the necessary connection in the drill string is obtained. Heretofore, with the provision of only a single crown block unit it was necessary to raise the kelly, swing it to one side of the derrick, disconnect it from the traveling block, and then utilize said block to pick up another section of pipe to connect in said string. After this was done it was then again necessary to disconnect the traveling block from 30 said section of pipe and go back to pick up the kelly and place the same in position for connection to the new section of pipe connected at the upper end of the drill string. The saving in time and labor is most important not only in performing a drilling operation but also in making up a tubing string to be inserted in a well. Similarly when the tubing or drill pipe is being pulled from the well for any reason whatever, the advantages of the double crown block units are obvious. It 35 is noted that in drilling operations whenever the kelly is disconnected to bring in another joint of pipe, the pump must be stopped. If said pump is stopped for too long a time caving in the bottom of the hole occurs and causes the drill pipe 40 remaining in said hole to become stuck or frozen therein. Therefore, by minimizing the time during which the pump is inoperative, the efficiency of the drilling is increased.

45 Since the units A and B include individual lines and independent draw works it is obvious that each can operate without interfering with the other. However, in some cases, such as when the pipe becomes stuck in the hole, it might be desirable to employ both of the crown block units. In 50 such case the units A and B are both moved to the center of the derrick and the traveling blocks of both are lowered and connected to the pipe. Then by operating both of the drums 24 and 42 of the draw works 25 and 43 it is possible to combine the pulling strength of both draw works to 55 release the pipe. It is noted that a particular type of crown blocks wherein three sheaves or pulleys are present, has been shown but the invention is not to be limited to any particular type 60 of crown block structures. There may be more or less sheaves or pulleys and the construction of the frame of the unit may be varied without departing from the invention. It is the movable mounting of the units A and B which brings about 65 the improved and advantageous results.

70 What I claim and desire to secure by Letters Patent is:

75 1. A derrick including, a supporting structure, crown block units mounted to undergo a straight line lateral movement at the upper end of the

structure, each unit being capable of an independent lateral movement relative to the other, means for moving said units transversely of the structure, and control means for actuating said moving means, said control means being locatable at a point removed from the crown block units.

2. A derrick including, a supporting structure, a pair of crown block units mounted so as to undergo a straight line transverse movement in 10 the same horizontal plane at the upper end of said structure, said units being separate from each other and being individually mounted, means for guiding said units to limit their movement to a straight line and prevent angular displacement thereof and means for simultaneously moving the units transversely of said structure. 15

3. A derrick including, a supporting structure, a transverse track mounted at the upper end of the structure, a crown block unit mounted to slide 20 on said track, and a second crown block unit also mounted to slide on said track and capable of a movement independent of the other unit, the units co-acting with the track whereby the 25 units are guided and lateral displacement with relation to the track is prevented, and means for imparting movement to the units, whereby both units may be simultaneously employed in performing well operations.

4. A derrick including, a supporting structure, 30 a transverse track mounted at the upper end of the structure, a crown block unit mounted to slide on said track, a second crown block unit also mounted to slide on said track and capable of a movement independent of the other unit, the 35 units co-acting with the track whereby the units are guided and lateral displacement with relation to the track is prevented, and fluid pressure actuated means for imparting movement to the units, whereby both units may be simultaneously employed 40 in performing well operations.

5. A derrick including, a supporting structure, a pair of angular parallel rails on the upper end of the derrick, a crown block unit comprising a 45 frame confined within and movable on the rails and having a plurality of sheaves mounted in the frame, a second crown block unit also comprising a frame with sheaves mounted therein and confined within and movable on the rails, and means for moving the units to desired positions on the 50 rails, whereby both units may be simultaneously employed in performing well operations.

6. A derrick including, a supporting structure, a pair of angular parallel rails on the upper end of the derrick, a crown block unit comprising a 55 frame confined within and movable on the rails and having a plurality of sheaves mounted in the frame, a second crown block unit also comprising a frame with sheaves mounted therein and confined within and movable on the rails, 60 and fluid pressure actuated means for moving the units to desired positions on the rails, whereby both units may be simultaneously employed in performing well operations.

7. A derrick including, a supporting structure, 65 a pair of angular parallel rails on the upper end of the derrick, a crown block unit comprising a frame confined within and movable on the rails and having a plurality of sheaves mounted in the frame, a second crown block unit also comprising a frame with sheaves mounted therein and confined within and movable on the rails, and means 70 remote from the units for controlling the movement of the units on the rails, whereby said units 75

may be manipulated so that both may be utilized to speed up well operations.

8. A derrick including, a supporting structure, a transverse track mounted at the upper end of the structure, a crown block unit mounted to slide on said track, an operating element connected to said unit, fluid pressure actuated means for imparting movement to the operating element to slide the unit, a second crown block unit entirely separate from the first unit and also slideable on the track, an operating element connected with said second unit, and fluid pressure actuated means for imparting movement to the last named operating element for sliding the second unit.

9. A derrick including, a supporting structure, a transverse track mounted at the upper end of the structure, a crown block unit mounted to slide on said track and confined against lateral and angular movement thereon, a cylinder adjacent one end of the track, a fluid pressure actuated piston movable in the cylinder and connected with the unit for sliding the unit on the track, a second crown block unit also slideable on the track and confined against lateral and angular movement thereon, a second cylinder at the end of the track opposite the first cylinder, and a fluid actuated piston movable in the second cylinder and connected with the second crown block unit for moving the same.

10. A derrick including, a supporting structure, a transverse track mounted at the upper end of the structure, a crown block unit mounted to slide on said track and confined against lateral and angular movement thereon, a cylinder adjacent one end of the track, a fluid pressure actuated piston movable in the cylinder and connected with the unit for sliding the unit on the track, a second crown block unit also slideable on the track and confined against lateral and

angular movement thereon, a second cylinder at the end of the track opposite the first cylinder, a fluid actuated piston movable in the second cylinder and connected with the second crown block unit for moving the same, and means remote from the cylinders for controlling the flow of pressure fluid thereto to control the movement of the pistons and the units.

11. A derrick including, a supporting structure, a transverse track mounted at the upper end of the structure, a crown block unit mounted to slide on said track, a cylinder adjacent one end of the track, a fluid pressure actuated piston movable in the cylinder and connected with the unit for sliding the unit on the track, a second crown block unit also slideable on the track, a second cylinder at the end of the track opposite the first cylinder, a fluid actuated piston movable in the second cylinder and connected with the second crown block unit for moving the same, a fluid conductor extending from each cylinder downwardly to the base of the derrick, and a control valve in each conductor for controlling the flow of fluid to the cylinders and pistons.

12. A derrick including, a supporting structure, a pair of angular parallel rails on the upper end of the derrick, a crown block unit comprising a frame movable on the rails and having a plurality of sheaves mounted in the frame, a second crown block unit also comprising a frame with sheaves mounted therein and movable on the rails, fluid pressure actuated means for moving the units to desired positions on the rails, whereby both units may be simultaneously employed in performing well operations, a fluid conductor extending downwardly from the fluid pressure means to the derrick floor, and a control valve in the conductor for controlling the flow of fluid therethrough to said means.

JAMES F. CHAPPELL. 40
